UNITED STATES PATENT OFFICE.

AUGUSTUS BROWN MORISON, OF JERSEY CITY, NEW JERSEY, ASSIGNOR TO
THE CO-OPERATIVE BUILDING PLAN ASSOCIATION, OF NEW YORK, N. Y.

DESIGN FOR THE EXTERIOR OF A HOUSE.

SPECIFICATION forming part of Design No. 20,093, dated August 12, 1890.

Application filed July 15, 1890. Serial No. 358,845. Term of patent 7 years.

To all whom it may concern:

Be it known that I, AUGUSTUS BROWN MORISON, of Jersey City, in the county of Hudson and State of New Jersey, have invented and produced a new and original Design for the Exterior of a House, of which the following is a specification, reference being had to the accompanying drawings, forming a part thereof.

10 Figure 1 represents a perspective view of a house showing my design. Fig. 2 represents a horizontal section or plan of the first story. Fig. 3 represents a horizontal section or plan of the second story.

15 Similar letters of reference designate corresponding parts in all the figures.

A house of this design consists of two stories with an attic third story within a gable roof, one side having an octagonal bay in the 20 first story, a projecting flat face to the second story, and a gable to the third story, the first story having a veranda, with a hip roof extending widthwise thereof and terminating at one end with an entrance-porch having a 25 gable roof, the rear end having a projecting portion from the first story with a hip roof, all as hereinafter more particularly to be de-

scribed in detail with reference to the drawings.

A B C designate the exterior of the first 30 and second stories and the attic. The first story has an octagonal bay *a* at the side thereof. The second story has a flat-faced projecting portion *b*, the face of which is about flush with the outer face of the bay, 35 the said portion having a gable roof *c*. The rear of the house at the first story has a portion *D* projecting therefrom with a hip roof *d*. The house has a gable roof *E F*, from which the aforementioned roof *c* projects, and 40 from which an additional portion *e* projects on the opposite side. The first story has at the front a veranda *G*, with a hip roof *g*, extending widthwise thereof and terminating with an entrance-porch *H*, having a gable 45 roof *h*.

What I claim as my design is—

The design for the exterior of a house, substantially as herein shown and described.

AUGUSTUS BROWN MORISON.
